UNITED STATES PATENT OFFICE.

ALBERT C. FISCHER, OF KANSAS CITY, MISSOURI.

SEAM-CLEAT FOR SHEET-ROOFING.

1,263,219.

Specification of Letters Patent. Patented Apr. 16, 1918.

Application filed December 12, 1916. Serial No. 136,433.

To all whom it may concern:

Be it known that I, ALBERT C. FISCHER, a citizen of the United States, residing at Kansas City, in the county of Jackson and State of Missouri, have invented certain new and useful Improvements in Seam-Cleats for Sheet-Roofing, of which the following is a specification.

This invention relates to an improvement in seam cleats for sheet roofing, and has for one of its objects to provide seam cleats in the form of nail spacing strips so that the cost of manufacture may be materially reduced, and that less labor, comparatively, will be required in securing them to the roofs of buildings than the seam cleats heretofore generally used. A further object is to provide such a construction that each cleat will be reinforced throughout its entire length to prevent buckling. The invention includes a metallic strip bent at uniform intervals of its length to provide loops or sockets for nail supports, nails maintained in the loops and provided with a sealing or adhesive member, so that when the nails are completely driven, the adhesive members will fill any unoccupied parts of the nail holes in the roof boards and roofing sheets, to exclude moisture, the loops at their lower ends being of flaring shape for this purpose.

With the above objects in view and others to be mentioned hereinafter the invention presents a novel construction, combination and arrangement of parts as described and claimed, and as illustrated in the accompanying drawing, wherein,—

Figure 1 is a view in side elevation of a part of a seam cleat. Fig. 2 is a plan view of the same. Fig. 3 is a reverse side view of the parts shown in Fig. 1. Fig. 4 is a view showing a roof board and roofing sheets in section, with a seam cleat applied thereto. Fig. 5 is a perspective view showing a part of a roof and parts of roofing sheets disposed in overlapped relation secured to the roof, in part, by means of the seam cleats. Fig. 6 is a sectional view through one of the loops, said view being a detail relating to Fig. 4, on an enlarged scale. Fig. 7 is a transverse section on line 77 of Fig. 3.

Referring now to the drawing for a more particular description, I provide narrow, metallic strips 8 of any suitable length and of suitable width, each preferably having a flange *a* at one of its edges, and formed at

longitudinal intervals with loops 9, each loop preferably being bell shaped or flaring at its lower end adjacent to the flange as indicated at *b*. Nails or similar impaling members 10 are disposed in the loops, each having a head of sufficient width that it may extend transversely, outwardly of the upper end of a loop, and having a length greater than the width of the strip; and that part of each nail which projects below the flange *a* and lower edge of the strip is provided with an appendage 11 of any suitable adhesive material impervious to moisture.

Numerals 12 indicate patches of adhesive material, each being secured upon the opposed parts of the metallic strips opposite to a loop, this being a desired feature generally, but may be omitted in some instances; and while the flange *a* for each strip is a desired feature and may be formed without appreciable expense, I do not wish to be understood as limiting myself to its use.

The device is of great advantage for securing the roofing sheets upon a roof as compared with roofing cleats heretofore used for that purpose, one of the reasons being that the nails are held in the loops ready to be driven into the roof boards 13, the time usually required by workmen in picking up the nails being saved; also workmen often cause nails to be scattered about when securing ordinary seam cleats to the roofing sheets of roofs, which frequently cause the sheets to become torn, and results in a loss of the nails; and it will be seen that, by use of the herein described device, the nails will be disposed at uniform distances from each other.

It will be understood that the roofing sheets 14 and 15 are disposed with their edges or parts adjacent thereto in overlapped relation, the device being used to secure them to the roof boards 13, and in operation the strip 8 may be manually disposed and maintained edgewise, the flange *a* engaging the uppermost sheet and the nails being disposed at right angles to the roof boards; and by use of a hammer or similar tool the nails are driven into the boards, through the sheets, until the flange *a* is firmly seated upon the uppermost roofing sheet.

The edges of the strip 8 are substantially parallel, and since the flange *a* is rectilinear, the parts of each strip between the loops

operate as keepers or holder-members for pressing the sheets 14 and 15 upon the roof, the upright part of each strip reinforcing the flange *a* to prevent buckling. During the operation of driving the nails, the adhesive parts 11 will, of course, be moved upwardly, but in each instance a part *c* (Figs. 4 and 6) will fill any part of the puncture or nail hole *d* not occupied by the nail itself, to prevent moisture from entering the wood, the bell-shaped part *b* of each loop also operating to retain a considerable portion *e* of said material, for the same purpose.

15 In instances where the roof is inclined, the strips, of course, are disposed inclinedly, and any suitable means may be employed for securing the sheets adjacent to their horizontal edges to the roof boards, keepers 20 in this instance being shown for that purpose.

It will be understood that the force delivered to the nail heads by the hammer will be communicated directly from the nail heads to the upper ends of the loops, since the heads of the nails bear upon and extend outwardly, transversely of the loops. In the manufactured product the strips have such a length that they may be conveniently handled by workmen, and the nails are prevented from being detached, either on ac-

count of their engagement with the walls of the loops, or by reason of the adhesive parts 11 or 12 so that when the device is used as a seam cleat, the nails will be in 35 position ready to be driven.

What I claim as my invention and desire to secure by Letters Patent is,—

1. A seam cleat consisting of a metallic strip, impaling members maintained at intervals substantially at right angles to and projecting beyond one of the edges of the strip, and adhesive appendages engaging the projecting parts of the impaling members.

2. A seam cleat consisting of an attenuated strip bent transversely to provide a flange at one of its edges and provided with loops, said loops being disposed with their longitudinal axes substantially at right angles to the strip and formed with flaring 50 ends opening adjacent to one of the edges of the strip, impaling-members in the loops projecting beyond the flaring ends thereof, and adhesive portions on the projecting parts of the impaling-members.

In testimony whereof, I have affixed my signature in presence of two witnesses.

ALBERT C. FISCHER.
